UNITED STATES PATENT OFFICE.

AXEL NELSON, OF PHILADELPHIA, PENNSYLVANIA.

AUTOMATIC RAILROAD-CROSSING GATE.

Application filed October 11, 1923. Serial No. 667,904.

To all whom it may concern:

Be it known that I, AXEL NELSON, a subject of the King of Sweden, residing at Philadelphia, in the county of Philadelphia and State of Pennsylvania, have invented certain new and useful Improvements in Automatic Railroad-Crossing Gates, of which the following is a specification.

This invention relates to railroad gates and has special reference to an electrically operated and train controlled railroad gate intended for use at street and country road intersections.

The principal and most important objects of the present invention are to provide a novel and improved form of operating means for railroad gates, said means being driven by an electric motor; to provide an electric circuit for the motor which will be closed by a train entering a certain portion of the railroad and kept closed as long as the train remains in the said portion or block to provide for disconnecting the operating means from the motor upon the gate reaching its lower position; and to provide gravity means for restoring the gate to lifted position and the parts of the operating mechanism to initial position upon the motor ceasing to operate through the breaking of the circuit caused by the passing of the train out of the block.

With the above and other objects in view the invention will now be described in one embodiment, particularly set forth in the appended claims and illustrated in detail in the drawings, wherein—

Figure 1 is a side elevation of a gate shown in its relation to a roadway, the latter and the housing for the operating mechanism being shown in section.

Figure 2 is a plan view of the housing or pit for the operating mechanism, a portion of the cover being broken away to show certain parts of the mechanism in the positions assumed when the gate is fully lowered.

Figure 3 is a view at right angles to Figure 1 and also partly in elevation and partly in section, the parts being shown in the positions assumed when the gate is fully raised.

Figure 4 is a plan view of the pit with the cover removed, the parts being in the positions shown in Figure 3.

Figure 5 is a diagram showing the track and circuit arrangement used with this invention.

Figures 6 and 7 are diagrammatic views

showing the manner in which four gates arranged in pairs may be operated under this invention.

In the present embodiment the invention has been shown in connection with the tilting or bascule type of gate but it will be readily understood that the operating mechanism may be used without change in other types of gates. For instance, a straight lift 60 or portcullis gate counterbalanced to remain normally raised may be substituted for the gate now shown. It is accordingly to be understood that the invention is not limited to the form shown wherein there is provided an inverted U-shaped standard 10 having a cross bar 11 journalled therein and carrying at each end a head or plate 12 to which is connected a respective side frame member 13 of the gate. These side frame members are 70 shown as being of the usual converging type and extend on both sides of the pivot bar 11 to form on one side the gate proper and on the other side counterbalance arms joined by a bar 14 supporting the counterbalance 75 weights 15, these latter being sufficiently heavy to keep the gate proper normally raised.

In the present instance the standard is shown as supported directly on the cover 85 plate 16 of a pit structure or housing 17 containing the operating mechanism. This operating mechanism includes a motor 18 on the shaft of which is fixed a gear 19 which meshes with a gear 20 carried on a shaft 21 90 supported in suitable bearings 22 mounted on the floor of the housing or pit. On this shaft 21 is fixed a driving gear 23 which meshes with a barrel or drum gear 24 under certain conditions in the operation. This 95 drum gear is fixed on a shaft 25 which is slidably and rotatably mounted in bearings 26. On the shaft 21 is also fixed a screw threaded friction drum 27 while the shaft 25 is provided with a fixedly secured friction 100 disk 28 having ribs or flanges 29 extending peripherally therearound and engaging the thread of the drum 27. The shaft 25 also carries a winding drum 30 which is preferably formed integral with the disk 28 and 105 has wound thereon a cable 31 which passes upwardly out of the pit through an opening 32 in the pit cover, being then led around an idler pulley 33 upwardly and over a pulley 34 and then downwardly having its end secured to the cross bar 14. Fixed to the bearing 26 adjacent the winding drum is a sub-

stantially hemispherical clutch member 35 and the winding drum is provided with a corresponding cavity 36. On the shaft 25, between the winding drum and the clutch member 35 is a coiled release spring 37.

In order that the operation of the device may be controlled in a purely automatic manner by the approach of a train, the arrangement shown in Figure 5 is used. 10 In that figure there is shown a pair of track rails insulated as at 39 to form a block 40. A suitable source of power, such as the generator 41 is connected to one of the rails of the block by a wire 42, the 15 other rail of the block being connected to the motor 18 by a wire 43, the motor and generator each having the usual ground connection.

In operation the gate is normally raised 20 and the parts of the operating mechanism are in the positions shown in Figures 3 and 4. Under these conditions, if a train enters the block 40 a circuit will be closed through the motor by reason of connection being established from one rail to the other through the axles of the train. The motor will now drive the shaft 21 in the direction of the arrow in Figure 4. This will cause the shaft 25 to be driven by 25 the gears 23 and 24 and, at the same time, the thread on the friction drum 27 will move the shaft 25 longitudinally in the direction of the clutch member 35 by reason of the engagement of the thread with the ribs or flanges 29. This longitudinal movement will continue until the parts are in the position shown in Figure 2 with the gear 24 out of engagement with the gear 23 and the end convolution of the 30 thread on the drum 27 in engagement with the side of the rib 29 nearest said drum. Meanwhile the cable has been wound on the winding drum and the counterweight end of the gate members raised so that 35 the gate proper is lowered to its closed position, being checked when horizontal by the usual strut 44. It is obvious that the parts are to be so adjusted that the disengagement of the gears 23 and 24 will take 40 place at the time when the strut engages the ground so that no damage will be done to the parts. The longitudinal movement of the winding drum brings it into contact with the spring 37 and then into engagement with the clutch member 35, the spring being compressed in the last part of this movement. At this time longitudinal movement will cease owing to the ribs 29 having reached the end of the screw thread on 45 the drum 27. Consequently all rotation of the shaft 25 will cease while the motor may continue to operate the shaft 21 so long as the circuit remains closed through the presence of the train in the block. As 50 soon as the train leaves the block the cir-

cuit will be broken and the motor will stop. Restoration of the parts to their normal positions will now take place through the gravitational effect of the counterweights which pull on the cable and start the same to unwind from the winding drum. This action causes the friction disk to rotate the threaded drum 27 in the direction opposite the arrow in Figure 4 and consequently the thread will engage the ribs 29 and longitudinal movement away from the member 35 will take place. The gear 24 will again come into mesh with the gear 23 and the movement will continue until the gate is fully raised and all parts restored to the positions occupied at the start of the gate closing operation.

Preferably the gears 23 and 24 and the friction drum and disk are provided with an oil bath 45.

It is obvious that the shaft 21 may be extended to operate two winding drums and thus actuate gates on opposite sides of the track, such an arrangement being indicated in Figures 3 and 4 where the extended shaft is shown as passing through a tunnel 46 extending under the track. This arrangement in a somewhat more fully developed manner is diagrammatically shown in Figures 6 and 7 which also show the manner in which double gates may be operated by means of a second cable 47 wound on each of the winding drums actuated directly from the shaft 21, these cables being led beneath roadway and over suitably positioned pulleys to operate the gates 48.

Changes in the arrangement and details of the invention will readily suggest themselves to engineers and others skilled in the art so that the invention is not to be confined to the precise embodiment herein described, but is to include all such as properly come within the scope claimed.

Having thus described the invention, what is claimed as new, is:

1. The combination with a normally open railroad gate; of a winding drum having a cable wound thereon and connected to the gate to effect closing of the gate upon the cable being wound up, a shaft carrying said drum, a motor driven shaft, normally meshing gears on said shaft, and means to effect disengagement of one of the gears from the other upon the gate being moved to closed position.

2. The combination with a normally open railroad gate; of a winding drum having a cable wound thereon and connected to the gate to effect closing of the gate upon the cable being wound up, a shaft carrying said drum, a motor driven shaft, normally meshing gears on said shafts and coating means on said shafts to cause one of the

gears to move longitudinally with respect to the other gear and thereby disengage from the last mentioned gear at a point in the operation corresponding to the closed position of the gate.

5. The combination with a normally open railroad gate; of a winding drum having a cable wound thereon and connected to the gate to effect closing of the gate upon the cable being wound up, a shaft carrying said drum, a motor driven shaft, normally meshing gears on said shafts, means to effect disengagement of one of the gears from the other upon the gate being moved to closed

10 position, and a brake mechanism for the winding drum operable upon completion of the closing movement of the gate.

4. The combination with a normally open railroad gate; of a winding drum having a cable wound thereon and connected to the gate to effect closing of the gate upon the cable being wound up, a shaft carrying said drum, a motor driven shaft, normally meshing gears on said shafts, coacting means on 20 said shafts to cause one of the gears to move longitudinally with respect to the other gear and thereby disengage from the last mentioned gear at a point in the operation corresponding to the closed position of the gate and a brake mechanism for the winding

25 drum operable upon completion of the closing movement of the gate.

5. The combination with a motor; of a shaft driven thereby, a second shaft journalled for rotative and longitudinal movement, meshing gears each fixed on a respective shaft, a winding drum fixed on the second shaft, a gate, a cable connected to said gate to operate the same and having one end wound on said winding drum, and coacting means on said shafts arranged to effect longitudinal movement of the second shaft upon rotation of the motor driven shaft whereby to disengage the gear on the 30 second shaft from the gear on the first shaft upon completion of a predetermined number of revolutions of the first shaft.

6. The combination with a motor; of a shaft driven thereby, a second shaft journalled for rotative and longitudinal movement, meshing gears each fixed on a respective shaft, a winding drum fixed on the second shaft, a gate, a cable connected to said gate to operate the same and having one end wound on said winding drum, and coaction means on said shafts arranged to effect longitudinal movement of the second shaft upon rotation of the motor driven shaft whereby to disengage the gear on the 35 second shaft from the gear on the first shaft

upon completion of a predetermined number of revolutions of the first shaft, said coacting means comprising a drum on the first shaft having a screw thread thereon, and a disk on the second shaft having a 65 peripheral rib engaging said thread, said threaded drum and disk also constituting friction gearing whereby the second shaft may drive the first shaft upon unwinding of the cable in opening movement of the 70 gate.

7. The combination with a motor; of a shaft driven thereby, a second shaft journalled for rotative and longitudinal movement, meshing gears each fixed on a respective shaft, a winding drum fixed on the second shaft, a gate, a cable connected to said gate to operate the same and having one end wound on said winding drum, coacting means on said shafts arranged to effect 80 longitudinal movement of the second shaft upon rotation of the motor driven shaft whereby to disengage the gear on the second shaft from the gear on the first shaft upon completion of a predetermined number of revolutions of the first shaft, and braking means engaging the winding drum to prevent driving thereof by the friction 85 gearing upon disengagement of the first mentioned gears.

8. The combination with a motor; of a shaft driven thereby, a second shaft journalled for rotative and longitudinal movement, meshing gears each fixed on a respective shaft, a winding drum fixed on the second shaft, a gate, a cable connected to said gate to operate the same and having one end wound on said winding drum, coacting means on said shafts arranged to effect longitudinal movement of the second shaft 95 upon rotation of the motor driven shaft whereby to disengage the gear on the second shaft from the gear on the first shaft upon completion of a predetermined number of revolutions of the first shaft, and coact 100 ing means comprising a drum on the first shaft having a screw thread thereon, and a disk on the second shaft having a peripheral rib engaging said thread, said threaded drum and disk also constituting friction 105 gearing whereby the second shaft may drive the first shaft upon unwinding of the cable in opening movement of the gate, braking means engaging the winding drum to prevent driving thereof by the friction gearing 110 upon disengagement of the first mentioned gears and train controlled means for closing a circuit through said motor.

In testimony whereof I affix my signature:
AXEL NELSON.
